REINFORCED MEMBER

Harry W. Hill, Sterling, Ill., assignor to North-western Barb Wire Company, Sterling, Ill., a corporation of Illinois

Application October 30, 1930. Serial No. 492,147

4 Claims. (Cl. 189—23)

This invention relates to improvements in a reenforced member, and more particularly to improvements in a reenforced member of a character highly desirable for use as a fence post incorporated in the construction of wire fences, although the invention may be used in connection with T-beams, I-beams, channel irons, Z-irons, and in other and various ways and manners as will be apparent to one skilled in the art.

10 In the making of posts, bars, beams, strips, etc., with or without flange-like portions thereon, the most desired accomplishment is to develop a member of this character which is exceedingly strong and rigid consistent with a very noticeable lightness in weight and marked saving of material.

Accordingly, it is an important object of this invention to provide a reenforced member of the character set forth herein which, while being very 20 made of relatively thin material, and being very light in weight, is provided with reenforcing means thereon arranged in such a manner as to enhance the strength of the member as a whole to a considerable extent.

25 It is also an object of this invention to provide a reenforced member of this character in which the reenforcing means are arranged so that the member is especially adapted to resist bending stresses.

30 Another object of this invention is the provision of a reenforced member which is provided with reenforcing on opposed faces thereof, the reenforcing on one of the faces running oppositely to that on the other of the faces to thereby enhance the total strength of the member.

It is still a further object of this invention to provide a reenforcing member, in the nature of a strip, or of a bar having a flange-like portion thereon, with oblique reenforcing on opposed 40 faces of the member, the reenforcing on one face running oppositely to that on the other face.

Still another object of this invention is the provision of a reenforced member in which the reenforcing means are integral with the member 45 and may be formed into the desired shape simultaneously with the forming of the member itself.

A still further object of this invention is the provision of a new and novel method of making 50 a reenforced member.

While some of the more salient features, characteristics, and advantages of a device embodying the present invention have been above pointed out, others will become apparent from the following disclosure.

The invention includes these and other features of construction and combination of parts hereinafter described, and shown in a preferred form in the drawing, as more particularly indicated by the claims.

On the drawing:

Figure 1 is a fragmentary side view of a reenforced T-bar or post, embodying principles of the present invention.

Figure 2 is a front view of the structure shown in Figure 1, taken from the right of Figure 1.

Figure 3 is a transverse sectional view of the structure shown in Figures 1 and 2, taken substantially as indicated by the line III—III of Figure 2.

Figure 4 is a view similar to Figure 3, showing a channel iron embodying principles of the present invention.

Figure 5 is a view similar to Figures 3 and 4, showing an I-beam embodying principles of the present invention.

As shown on the drawing:

In the illustrated embodiment of this invention, there is shown a reenforced T iron member arranged to function very expeditiously and durably as a fence post. The post is mounted upright and either wire strands or wire netting is attached thereto in the forming of the fence. Obviously, it is highly desirable to have the post as light in weight as possible for economical reasons, and still the post must be sufficiently rigid to support various loads which bear against the fence.

The T iron post, comprising a leg flange 6 and a cross flange 7, is in this instance provided

with spaced aligned notches 8 along each side edge of the cross flange 7 so that wires forming a part of or supporting a fence may be readily engaged around the post and will be held in proper position at all times. Consistent with the aforesaid purpose of making the post as strong and

rigid as possible without undue bulk, the leg flange 6 is reenforced on both side faces thereof, the reenforcing in this instance consisting of a continuous rib 9 on one side face of the flange 6, and a continuous rib 10 on the other side thereof.

It will be noted that each of the ribs 9 and 10 runs obliquely back and forth from one side edge of the leg 6 to the other side edge of the leg 6. Each rib also runs in its oblique manner

substantially the full length of the post. It should be distinctly noted, however, that the rib 9 runs oppositely to the rib 10, whereby the strength of the post as a whole is greatly enhanced.

110

In making the T iron, a piece of stock iron or an ingot is preferably rolled into the desired shape, and at least the last set of rolls is preferably grooved in the proper manner to form the 5 ribs 9 and 10, whereby these ribs are rolled upon the finished member, simultaneously with the forming of the member. Of course, the device may be made in other ways without departing from the spirit and scope of the invention, such, 10 for example, as die casting.

Although I have disclosed and described the invention hereinabove as being in the shape of a T iron, it is to be understood that the invention may be made in the shape of I-beams, Z-irons, 15 channel irons, strips, bars, or any other equivalent form depending upon where it is desired to use the invention.

In Figure 4, I have shown a channel iron 11 embodying principles of the present invention. 20 The channel iron includes a pair of flange-like side portions 12 and 13 respectively, each of which is provided with a reenforcing rib on each face thereof, these ribs being designated as 14, 15, 25 16, and 17 respectively. These ribs, in each instance, are identical in form with the ribs 9 and 10, and it will be noted that the ribs 14 and 15 on the side 12 run oppositely to each other, while the ribs 16 and 17 on the side 13 also run oppositely to each other. The channel iron 11 may be 30 formed in substantially the same manner as hereinabove set forth for the T-iron post.

In Figure 5, I have shown an I-beam comprising a central leg 18 and an upper cross flange 19, and a lower cross flange 20. The central leg flange 18 is provided on each side thereof with an 35 obliquely running reenforcing rib, 21 and 22, respectively. These ribs also run oppositely to each other and strengthen the leg 18 of the I-beam. The I-beam may also be rolled or die cast as 40 desired.

From the foregoing, it will be apparent that I have provided a reenforced member which is exceedingly strong and rigid, and yet made of relatively thin and light material, the member being 45 reenforced in such a manner as to greatly enhance its strength and yet add but very little to

the weight of the member as a whole. Moreover, the reenforcing is preferably integral with the member itself, the reenforcing being preferably formed simultaneously with the forming of the member. In addition, it will be noted that the reenforcing is preferably mounted on opposite faces of a portion of the member, and preferably runs obliquely, the reenforcing on one face being opposite to that upon the other face of the member. It will also be noted that the reinforced member is extremely durable, suitable for a variety of purposes, easy to handle, and very expeditiously and economically manufactured.

I claim as my invention:

1. A fence post comprising a reenforced member having a plurality of flange-like portions, and one of said portions having oblique reenforcing on each side thereof being in the form of integral ribs, the reenforcing on one side running oppositely to that on the other side.

2. A fence post comprising a metallic strip having reenforcing on opposed faces thereof, said reenforcing being in the form of a rib integral with said strip and running along the length thereof obliquely back and forth substantially from one side edge of said faces to the other, the reenforcing on one of said faces running oppositely to that on the other of said faces.

3. A fence post comprising a metallic strip having reenforcing means on opposite faces thereof formed integrally with said strip, said reenforcing running obliquely across said faces and the reenforcing on one face running oppositely to that on the opposed face.

4. A fence post of substantially T bar construction having a front portion and a rear portion thereof and reenforcing on opposed faces of said rear portion, said reenforcing being in the form of a rib integral with said rear portion and running along the length thereof obliquely back and forth substantially from one side edge of said faces to the other, the reenforcing on one of said faces running oppositely to that on the other of said faces.
